153,878

DESIGN FOR AN ELECTRIC LIGHT WALL BRACKET

Arthur A. Johnson, New Bedford, Mass., assignor
to John I. Paulding, Inc., New Bedford, Mass.,
a corporation of Massachusetts

Application December 19, 1947, Serial No. 143,246

Term of patent 14 years

(Cl. D48—4)

To all whom it may concern:

Be it known that I, Arthur A. Johnson, a citizen of the United States, residing at New Bedford, in the county of Bristol and State of Massachusetts, have invented a new, original and ornamental Design for an Electric Light Wall Bracket, of which the following is a specification, reference being had to the accompanying drawings, forming part thereof.

Figure 1 is a front elevation of an electric light wall bracket, showing my new design.

Figure 2 is a right hand edge elevation of the same.

Figure 3 is a top plan view of the same.

I claim:

The ornamental design for an electric light wall bracket, as shown.

ARTHUR A. JOHNSON.
